HYDRAULIC REMOTE CONTROL SYSTEM

Lemuel E. Dougherty, Miami, Fla.

Application September 21, 1942, Serial No. 459,176

7 Claims. (Cl. 60—54.5)

This invention relates to an improved hydraulic remote control of the type wherein a single tube is used as connection between the controlling station, usually called the transmitter, and the controlled station, usually called the receiver. One such system is shown in my copending application Serial No. 449,942, filed July 6, 1942.

In my aforementioned copending application is shown a locking means for control systems of this type which consists of a valve apparatus located in the system between the transmitter and receiver which normally prevents passage of fluid between the transmitter and receiver thus locking the control system against unauthorized movement. This fluid locking means effectively holds the control from movement due to vibration or any external force applied at the receiver, but in installations where the receiver is subject to large variations in temperature the resultant expansion or contraction of the hydraulic fluid in the receiver cylinder causes some movement of the piston therein and consequent undesired movement of the controlled member.

It is, therefore, the principal object of this invention to provide a hydraulic remote control incorporating a locking or holding means effectively preventing unauthorized movement of the movable element in the receiving end of the equipment, regardless of changes in temperature, leakage of fluid or other causes which would tend to cause or allow such movement.

Other objects and advantages of this invention will be apparent during the course of the following detailed description.

In the accompanying drawings of apparatus illustrative of this invention,

Figure 1 is an assembly view, with parts sectioned vertically, of the control equipment.

Figure 2 is a cross sectional view taken substantially on its respective line shown in Figure 1.

Figure 3 is an enlarged cross sectional view taken substantially on its respective line shown in Figure 1.

Figure 4 is an enlarged vertical section of a portion of the receiver showing a modified form of that shown in Figure 1.

Figure 5 is a cross sectional view taken substantially on its respective line shown in Figure 4.

Referring to Figure 1, the letter A designates the transmitter assemblage and the letter B the receiver assemblage which are connected together by the fluid conduit or tube 36. The transmitter assemblage A comprises a supporting frame 10 upon which is mounted a cylinder 11. A fluid actuating piston 12 is slidably in the cylinder.

This piston is relatively long and includes the piston head 13 having minute transverse openings 14 therein. The upper end 20 of the piston is provided with the seal 16 to prevent leakage of fluid past this end of the piston thus forming a fluid chamber 22 in the cylinder between the heads of the piston. The lower head 13 of the piston is provided with a yieldable sealing cup 15 of a nature which will prevent flow of fluid upwardly but will permit fluid to pass through the openings 14 into the lower chamber 23 of the cylinder when the pressure in chamber 22 is greater than exists in chamber 23.

Fluid from a supply tank flows by gravity or other means through the tube 18 and connecting fitting 9 into the chamber 22 through the inlet port 17. As the distance between the heads of the piston 12 is equal to its travel in the cylinder, it is apparent that the port 17 is open at all times and the chamber 22 always filled with fluid at not less than atmospheric pressure. The compensating port 18 is provided to permit fluid in the pressure part of the system, when there is an excess thereof, to return to the supply tank at the most upward movement of the piston when this port 18 is uncovered, as will be subsequently referred to.

The operating handle 29 is integral with the lever 26 which is pivoted at 28 upon the frame 10. The connecting rod 24 has a pivot connection to the lever at 25 and at its other end is pivoted at 21 to the upper end 20 of the piston 12. A spring supporting rod 30 is pivoted at 27 to the lever 26 and is slidably supported within a collar 31. The latter is trunnioned in the frame 10 by the pivot bolts 33 and 34 as shown in Figure 2 of the drawings. A spring 33, under compression, is supported upon the rod 30, being seated at one end in the collar 31 and at its other end being held in compressed relation upon the rod by means of a retaining disc 34 held on the rod in adjustable relation by means of a nut 35. It is of course apparent that the compression force of the spring acts through the linkage to maintain the fluid in the chamber 23 in the lower part of cylinder 11 under pressure. Movement of the handle 29 and lever 26 increases or decreases the compression of the spring 33, but the leverage and linkage connecting this spring with the piston is so arranged, as set forth in my aforementioned copending application, that it exerts a substantially constant pressure force upon the fluid in the cylinder regardless of the position of the piston therein throughout its range of travel. Stop shoulders 37 and 32 are provided upon the

spring rod 30 for contact with the collar 31 in order to limit the travel of the piston 12. The piston of the transmitter is given slightly greater travel than the piston of the receiver, to be subsequently described, so that the compensating port 18 can be uncovered if required.

Referring to the receiver B, the same is in many respects similar to the transmitter assemblage. It is provided with a frame 40 which supports the cylinder 41 having a piston 42 slideable therein. This piston is provided with a sealing cup 43. A lever 46 is pivoted at 49 to the frame 40 and at its other end pivotally connected at 47 to the connecting rod 45 which has pivotal connection at 44 with the piston 42. An angular extension of the lever is provided with the openings 50 for the connection of control rods, etc., in a manner well understood by those skilled in the art to which this invention relates. The details of the spring assemblage are substantially the same as that of the transmitter. The spring supporting rod 52 is pivoted at 48 to the lever 46 and is slidably supported in the collar 51 which is trunnioned in the frame 40 similar to the collar 31 in frame 10, as shown in Figure 2. A spring 57 is seated at one end in collar 51 and held under compression by means of a retaining disc 54 held upon the rod by a nut 55. Stop shoulders 56 and 58 upon the rod 52, limit the travel of the piston 42 by seating against the collar 51.

The locking apparatus associated with the receiver assemblage is contained in the casing 60 which is attached to the end of the cylinder 41. A chamber 64 is provided in the central part of the casing, through which extends the rod 62 which is rigidly attached to the piston 42. Fluid connection from the receiver cylinder to the transmitter cylinder is accomplished by means of the chamber 64 and passage 65 in the casing 60, the connecting fitting 61 and the tube 36. An extension 63 is provided for the casing 60 to accommodate the rod 62 in downward movement of the piston.

Referring to the assemblages A and B as shown in Figure 1, it is apparent that with the system filled with the proper quantity of a hydraulic fluid, downward movement of the transmitter piston 12 will cause a corresponding upward movement of the receiver piston 42. After such movement has taken place an upward movement of the transmitter piston will cause corresponding downward movement of the receiver piston 42 by action of the spring 57. As the springs of transmitter and receiver exert a substantially equal constant pressure force upon the fluid in the system, regardless of the positions of their respective pistons in the cylinders, it is a substantially balanced system with little tendency on its own part to assume a position other than where moved. In some positions there may be a slight unbalance of forces between the springs of transmitter and receiver, but the locking apparatus, to be subsequently described, prevents any undesired movement.

Compensation for loss, expansion or contraction of the hydraulic fluid is accomplished by movement of the transmitter piston 12 to its uppermost position, with the stop 32 against the collar 31, at which point the compensating port 18 is uncovered and is open into the pressure chamber 23 in the cylinder 11 below the piston sealing cup 15. If there is an excess of fluid in the system, downward movement of the receiver piston 42 will continue until it has reached its low-

est position with the stop 56 against the collar 51 and the excess fluid will escape through the compensating port 18 into the supply tank. If there is a deficiency of fluid in the system, the receiver piston 42 will reach its lowest position before the transmitter piston 12 has reached its corresponding upper position. In this case, further upward movement of the transmitter piston, by exertion of force on the handle 29, will cause the fluid pressure in the chamber 23 to fall below that in chamber 22 which is connected to the supply tank. Therefore fluid will pass through the openings 14, around the sealing cup 15 and into the chamber 23, thus re-establishing the proper quantity in the system. In either case of an excess or deficiency of fluid in the system, if the operating handle 29 is moved until the stop 32 strikes the collar 31, and then released, the transmitter piston will return to its normal position closing the compensating port 18 from the pressure chamber 23, through the action of the spring 33, and the pistons will be re-established in proper relation.

Referring to Figure 3, the fluid chambers 75 and 76 are provided in opposite sides of the casing 60. The flexible diaphragms 83 and 84 are supported in these chambers 75 and 76 respectively. The spring 77 is held under compression upon the diaphragm 83 by means of the cap 79 which is adjustable in the spring barrel 78. The spring 80 is similarly held under compression upon the diaphragm 84 by the cap 82 which is adjustable in the spring barrel 81. The passages 66 connect the chambers 75 and 76 with the chamber 64 so that the fluid pressure in the system is present upon the inward sides of the diaphragms at all times. The rod 71 is slidably supported in the casing and attached to the diaphragm 83, with the shoulder 72 provided to seat against the casing and limit its outward movement. The rod 73 is slidably supported in the casing and attached to the diaphragm 84, with the shoulder 74 provided to limit its outward movement. The fixed locking member 68 is rigidly attached to the casing and supports the pin 70 on which the hinged locking member 69 is pivotally mounted. The inward sides of the locking members are formed to accommodate the rod 62 which passes between them and is attached to the piston 42, as shown in Figure 1. It is apparent that force exerted by the rod 71 against the hinged locking member 69 will tend to clamp the rod between the locking members and there will be a high frictional resistance against its movement.

In considering the forces actuating the locking mechanism it should be noted that the fluid exposed area of diaphragm 84 is greater than that of the diaphragm 83, and the spring 80 heavier than the spring 77. The normally constant fluid pressure in the system exerts a force outwardly upon the diaphragms proportionate to their respective areas, so there is normally a force from the fluid pressure acting to move rod 71 outwardly and a greater force acting to move rod 72 outwardly. The spring 77 exerts a greater force than the normal fluid pressure acting upon the diaphragm 83, so there is a resultant inward force on rod 71 which acts upon the hinged locking member 69, thus clamping the rod 62. The spring 80 exerts a force slightly less than the force of the fluid pressure acting upon diaphragm 84 so there is normally a slight resultant force acting outwardly on rod 72 so the shoulder 74 rests against the casing. It is apparent that the

forces from the springs 77 and 80, acting through the rods 71 and 73 respectively, act in opposite relation upon the locking member 69; but the area of diaphragm 84 is such that the normal fluid pressure acting upon it will hold rod 73 with its shoulder 74 against the casing, in the position shown in Figure 3, so it will have no effect upon the locking member.

When the operator desires to move the control he exerts force on the operating handle 29 with a resultant increase or decrease in the fluid pressure in the system. If the transmitter piston is moved downwardly, so that the fluid pressure increases a predetermined amount the force of the fluid pressure upon diaphragm 83 will be greater than the force of the spring 77 and the rod 71 moves outwardly removing the pressure of the locking member 69 upon the rod 62. If the transmitter piston is moved upwardly so that the fluid pressure decreases a predetermined amount, the force of the fluid pressure upon diaphragm 84 will be less than the force of the spring 80 and the rod 73 will move inwardly and rest against the locking member 69. As the spring 80 is stronger than the spring 77, this decrease in fluid pressure allows the spring 80 to overcome the force exerted upon the locking member 69 by the spring 77, thus relieving the clamping pressure on the rod 62 and the receiver piston 42 will be free to move.

It is thus seen that under the normal fluid pressure in the system, as determined by the spring means of the transmitter, the receiver piston will be held against movement by the clamping action of the locking member through force exerted by the spring 77, but that a predetermined increase or decrease in fluid pressure, caused by the operator's exertion of force upon the transmitter operating handle, removes the pressure upon the locking member and allows free movement of the receiver piston. As the receiver piston is normally held against movement, any expansion, contraction or leakage of the hydraulic fluid in the system will cause movement only in the transmitter; and the control system is held against movements due to external forces such as vibration.

In Figures 4 and 5 is shown a modified form of locking apparatus. Referring to Figure 4, there is shown a portion of the receiver cylinder 41' with the piston 90 equipped with the sealing cup 91 slidable therein. The rod 96 is attached to the piston by means of a ball and socket connection. It thus has a limited swivel action. The casing 92 is attached to the end of cylinder 41' and contains the chamber 93 in which the locking members are located. The locking member 100 is pivotally mounted between the flanges 98 which extend into the chamber 93. An extension 97 is provided on the casing to accommodate the rod 96. Fluid connection from the transmitter cylinder is by means of the tube 36', the connecting fitting 94 and the passageway 95, so that fluid pressure from the transmitter is present at all times in the chamber 93 and in the receiver cylinder.

Referring to Figure 5, the flexible diaphragms 105 and 106 are mounted in the fluid chambers 114 and 113 in opposite sides of the casing 92. The spring 109 is held under compression upon the diaphragm 105 by means of the cap 108 which is adjustable in the spring barrel 107. The spring 112 is held under compression upon the diaphragm 106 by means of the cap 111 which is adjustable in the spring barrel 110. The rod 122 is attached to the diaphragm 105 and slidably

5 supported in the casing with the shoulder 123 limiting its outward travel. The rocking member 120 is pivoted to the casing at 121 and pivotally connected at 119 to the rod 117. The latter is slideable in the casing and attached to the diaphragm 106 with the shoulder 118 limiting its travel. The locking members 99 and 100 are pivotally mounted upon the pin 101, which is supported by the flanges 98 shown in Figure 4. The passages 115 and 116 connect the chambers 114 and 113 with the chamber 93 so that fluid pressure from the transmitter is present on the inner sides of diaphragms 105 and 106.

10 In this form of construction, unlike that shown in Figure 3, the diaphragms may be of equal size, if desired. In that case the spring 109 is 15 stronger than the spring 112. Force of the spring 109 is greater than the force from the normal fluid pressure upon the diaphragm 105, so there is a resultant force exerted inwardly by the rod 122 upon the locking member 99. Force of the spring 112 is less than the force from the normal fluid pressure upon diaphragm 106, so there is a resultant force transmitted through 20 the rocking member 120 inwardly upon the locking member 100. Under normal fluid pressure these two forces acting upon opposite sides of the locking members are substantially equal and the locking members assume a position as shown 25 in Figure 5 and clamp the rod 96 against movement.

30 It is apparent that an increase in fluid pressure upon the diaphragm will cause them to move outwardly against the force of their springs. 35 Outward movement of diaphragm 106 causes an opposite movement of locking member 100 which moves inwardly until it strikes the stop 124 at which point no further movement is possible. Diaphragm 105 can move outwardly, thus releasing the pressure on locking member 99, until the shoulder 123 on rod 122 strikes the casing. 40 At this point no force is exerted on the locking member 99, so there is no clamping action on rod 96 and the receiver piston is free to move. A decrease from the normal fluid pressure upon the diaphragms will cause them to move inwardly 45 due to the force exerted by their springs. Inward movement of diaphragm 105 causes an inward movement of the locking member 99 until it strikes the stop 124. Inward movement of diaphragm 106 allows an outward movement of the locking member 100 which releases the clamping pressure on the rod 96 and allows movement 50 of the receiver piston.

55 While for purposes of illustration in the drawings considerable clearance is shown between the stops and other parts of the locking apparatus, in practice the parts may be fitted closely together and only very slight movements of the diaphragms will be required to impose or release 60 the force upon the locking members.

Various changes in the shape, size, arrangement of parts and details of construction may be 65 made to the forms of the invention herein shown, without departing from the spirit of the invention or the scope of the claims.

I claim:

70 1. In a hydraulic remote control system having a receiver assemblage with a movable element, a locking device comprising clamping means adapted to offer frictional resistance to movements of the movable element in the receiver assemblage, spring means normally exerting force upon said clamping means for the operation thereof, spring means of greater force

opposing the force of said spring means acting upon said clamping means, and means whereby force from the fluid pressure in the system opposes the force of said last named spring means normally preventing any action on its part but adapted to allow such action and consequent overcoming of the force from said first named spring means upon predetermined decrease in fluid pressure from the normal fluid pressure in the system.

2. In a hydraulic remote control system having a receiver assemblage with a movable element, a locking device comprising locking means adapted to oppose movements of the movable element in the receiver assemblage, means normally exerting force upon said locking means for the operation thereof, means of greater force opposing the force of said first named means acting upon said locking means, and means whereby force from the fluid pressure in the system opposes the force of said last named means normally preventing any action on its part but adapted to allow such action and consequent overcoming of the force from said first named means upon a predetermined decrease in fluid pressure from the normal fluid pressure in the system.

3. In a hydraulic remote control system having a receiver assemblage with a movable element, a locking device comprising a rod connected to the movable element in the receiver assemblage, two locking members disposed to exert clamping action upon said rod, stop means for said locking members so that if either of said locking members rests against the stop the clamping action upon said rod will be relieved, spring means whereby force is normally exerted upon one side of one of said locking members, means whereby force from the fluid pressure in the system opposes the force of said spring means, said force from the fluid pressure means being normally less than the force from said spring means, means whereby force from the fluid pressure in the system is normally exerted upon the opposite side of the other of said locking members, spring means whereby force from the spring opposes the force from said last named fluid pressure means, the force from said last named spring means being normally less than the force from said last named fluid pressure means, and means whereby under the normal fluid pressure in the system the resultant force of the opposing forces of said first named spring means and said first named fluid pressure means is substantially equal to the resultant force of the opposing forces of said last named fluid pressure means and said last named spring means, each of said resultant forces acting upon opposite sides of said locking members in a manner to exert clamping action upon said rod, but so arranged that an increase or decrease from the normal fluid pressure in the system will cause movement of said locking members until one of said locking members rests against said stop means thus relieving the clamping action of said locking members upon said rod.

4. A locking device for hydraulic remote control systems having a receiver assemblage with a movable element, a rod connected to the movable element in the receiver assemblage, a pivoted locking member adapted to clamp said rod against movement, a compression spring, a flexible diaphragm whereby force from fluid pressure opposes the action of said spring, a compression spring of

greater force than said first named spring, a flexible diaphragm of greater area than said first named diaphragm, whereby force from fluid pressure opposes the action of said last named compression spring, and said parts being so arranged that force is normally exerted upon said locking member for the operation thereof in clamping said rod but that an increase or decrease in fluid pressure from the normal fluid pressure acting upon said diaphragms will cause a lessening of force exerted upon said locking members.

5. A locking device for hydraulic remote control systems having a receiver assemblage with a movable element, a rod connected to the movable element in the receiver assemblage, two locking members adapted to clamp said rod between them against movement, stops for each of said locking members, a compression spring, a flexible diaphragm whereby force from fluid pressure opposes the action of said spring, a compression spring of less force than said first named spring, a flexible diaphragm whereby force from fluid pressure opposes the action of said last named compression spring, a rocking member associated with said last named compression spring and diaphragm for the transference of force therefrom, and said parts being so arranged that force is normally exerted upon each of said locking members for the operation thereof in clamping said rod but that an increase or decrease in fluid pressure from the normal fluid pressure acting upon said diaphragms will cause one of said locking members to move against its stop thus relieving the clamping pressure upon said rod.

35 6. In a locking mechanism for hydraulic remote control systems the combination of a casing, locking means in the casing including a movable part, and fluid pressure actuated means for controlling the locking action of said movable part comprising pressure actuated diaphragms, and fluid pressure countering springs urging said diaphragms in a direction counter to fluid pressure, said diaphragms being of unequal fluid pressure exposed area and one of said springs having a greater force acting counter to fluid pressure than the other spring.

7. In a hydraulic remote control system, the combination of a transmitter cylinder, a receiver cylinder, a piston in each of said cylinders, a conduit connecting said cylinders, a hydraulic control fluid in said conduit and cylinders between said pistons, means acting upon said transmitter piston to maintain a substantially constant fluid pressure in excess of atmospheric pressure in said cylinders and conduit, means acting upon said receiver piston to maintain a substantially equal balancing force to said means acting upon said transmitter piston, locking means and means for rendering said locking means normally effective to prevent movements of said receiver piston and for rendering said locking means ineffective upon predetermined increase or decrease in the fluid pressure in the system, said last named means comprising a plurality of diaphragms of predetermined relative areas, means for placing said fluid in direct engagement with one side of each of said diaphragms, a plurality of springs of predetermined relative strengths in engagement with the other side of said diaphragms, and means for controlling the actuation of said locking means by the differential action of said diaphragms and said springs.

LEMUEL E. DOUGHERTY.
